UNITED STATES PATENT OFFICE

DAVID C. STEINBERG, OF PHILADELPHIA, PENNSYLVANIA

DESIGN FOR A SMOKING STAND

Application filed December 4, 1930. Serial No. 37,881. Term of patent 7 years.

To all whom it may concern:

Be it known that I, DAVID C. STEINBERG, a citizen of the United States, and a resident of Philadelphia, county of Philadelphia, State of Pennsylvania, have invented, a new, original, and ornamental Design for Smoking Stand, of which the following is a specification, reference being had to the accompanying drawings, forming a part thereof, wherein:

I claim:

The ornamental design for a smoking stand as shown.

DAVID C. STEINBERG.
